CLAIM

I claim the ornamental design for a grilling utensil, as shown and described.

DESCRIPTION

FIG. 1 is an oblique view of the invention;

FIG. 2 is the top view thereof;

FIG. 3 is the right side view and the left side view thereof; FIG. 4 is one end view and the opposite end view thereof; and,

FIG. 5 is the bottom view thereof.

The intended use of this invention is to provide decorative grilling utensils on a grill.
